PUMPING APPARATUS

William C. Brooks, Niagara Falls, N. Y., assignor
to Niagara Alkali Company, Niagara Falls, N. Y.

Application June 20, 1945, Serial No. 600,437

2 Claims. (Cl. 103—87)

1

This invention relates to pumping devices or apparatus for use in connection with the pumping of liquids, and more particularly liquefied gases and corrosive liquids, such for example as liquid chlorine, anhydrous hypochloric acid, liquid sulfur dioxide, hydrogen sulfate and other liquids.

One of the objects of this invention is to provide a pumping device of this kind in which the rotor of the motor which operates the pump operates in a gas phase only and not in contact with the liquid being pumped. Another object of this invention is to provide a pump of this kind which is so constructed that the usual stuffing boxes can be eliminated. Other objects and advantages of this invention will appear from the following description and claims.

Pumping devices have heretofore been provided for use in connection with liquids of this type in which the rotary part of the motor operates in the liquid which is being pumped, which, however, has proven unsatisfactory because of the additional power required to operate the rotary part of the motor in a liquid medium and because of the possibility that the parts of the motor may be damaged by the liquid. In my improved pump, I have provided an upright chamber with the upper portion thereof sealed so as to form an air-tight pneumatic dome in which the rotary part of the motor may operate in air or in a gas phase, the lower portion of the chamber through which the liquid being pumped flows and in which the pump is located being in communication with the upper portion, so that the liquid being pumped may enter the upper portion. The rise of liquid into the upper portion of the chamber is resisted by the air or gas cushion confined in the upper portion.

Any suitable means may be provided for producing such construction, and in the particular embodiment of the invention shown in the accompanying drawing, which is a vertical central sectional elevation of a pumping apparatus embodying this invention, I have provided an upright chamber including a substantially tubular or cylindrical upper portion 5, which is tightly sealed to prevent escape of air or other gas from the interior of the chamber. The chamber also includes a lower portion 6 in which the pump is located and into which liquid is admitted by means of an inlet pipe 7 and discharged through an outlet or discharge pipe 8. The lower portion 6 of the chamber is also formed to provide a pump housing 9 of any suitable type in which a rotor 9a is arranged. The middle or inlet por-

2

tion of the rotor receives liquid from an upright passage 10 for the liquid to be pumped. The upper and lower portions of the housing may be secured together in any suitable manner and suitable packing means 12 are provided to prevent escape of gas or liquid through the joint between the two portions of the housing.

If desired, a plate or partition 14 may be interposed between the upper and lower portions of the housing, but this plate or partition is not intended to form a seal to separate the two portions of the housing from each other, the plate in the construction shown being provided with a central hole or aperture 15 therein through which liquid and gas may pass from one portion of the housing to the other, and preferably a driving shaft 16 secured to the pump impeller 9a also passes through this hole. This plate may be a part of the pump housing and serves to prevent excessive surging or splashing of the liquid in the upper portion of the housing.

The upper or tubular portion 5 of the chamber is provided with a head 18 which is suitably secured to the upper end of the tubular or cylindrical member 5 to form a tight joint therewith and this head is preferably provided with a bearing for the upper end of the shaft 16. This bearing may be of any suitable construction, and as shown, is formed in a substantially cylindrical bore or recess in the axial portion of the head, and includes a bushing 19 which may be made of graphite or other suitable material not attacked by the gas which may be contained in the upper part of the chamber. This bearing is preferably self-lubricating. The axial recess or bore in the head 18 in the particular construction shown extends into an integral tubular part or hollow lug 20 extending upwardly from the head 18 and the upper end of which is tightly closed by any suitable means, such as a cap 21. As a result of this construction, it will be noted that the upper end of the cylinder 5 is tightly sealed, without requiring any stuffing box, and consequently, air or vapor from the liquid being pumped, or a mixture of both, will be entrapped in the upper portion of the chamber 5 and may be compressed to different pressures, depending upon the pressure of the liquid in the lower part of the chamber. The tubular part 5 of the chamber is made of sufficient height so that regardless of the pressure of the liquid in the lower part of the chamber, there will always be a considerable space filled with air or other gas in the upper part of the chamber, and for this purpose the clear space in the tubular part

or cylindrical chamber 5 below the bottom of the rotor should be at least equal in height to the distance from the bottom of the rotor to the head 18. If the apparatus is designed to operate on liquids at relatively high pressures, the height of the clear space should be increased to prevent the liquid level from rising to the lower end of the rotor.

A motor is provided at the upper end of the chamber and constructed so that the rotatable part is located within the chamber and operates in the air or other gas trapped therein. Any suitable or desired type of motor may be employed for this purpose, and in the construction shown by way of example, I have provided an induction motor with a stator thereof arranged on the outside of the tubular chamber part 5 and with the rotor thereof arranged within the chamber. For this purpose, the upper portion 24 of the wall of the tubular part 5 of the chamber is made of greatly reduced thickness and a stator core 25 is arranged about the relatively thin part 24 of the housing, preferably in such a manner that the core itself forms a reinforcement for the thin portion of the housing. 26 represents the usual stator winding. The rotating magnetic flux of the stator acts through the thin walled portion 24 of the tubular part 5 on a rotor 27 which may be of any suitable or usual construction, and which is secured to the upper part of the shaft 16. The thin walled portion 24 of the tubular part 5 of the upright chamber or housing must, of course, be made of a non-magnetic material. Since the construction and operation of induction motors is well understood, no further description is deemed necessary. The stator core and its winding may, if desired, be enclosed in a head or enclosure 28 in the form of a cap resting on the head 18 of the housing and having a depending part surrounding the stator, and the lower portion of the cap may be closed by means of a ring or annular disk 30 welded to or otherwise secured to the tubular housing part 5. Cooling fins or vanes 31 may be provided on the outer surface of the stator enclosing cap 28 to dissipate heat developed in the stator. This cap protects the stator against damage, but may be omitted, if desired.

The shaft 16 may be journalled at its lower end in an upright aperture formed in the base portion 33 of the lower portion of the pump chamber and a bearing bushing 34 of a material, which is not attacked by the liquid which is being pumped, is provided. The lower part of the aperture in the base may be provided with internal screw threads 35 and an adjusting screw 36 having a stem 37 extending into the bearing bushing may form the lower thrust bearing for the shaft, a ball 38 being interposed between the stem 37 and the lower end of the shaft 16. The aperture in the base extends through the same and the lower end thereof may be suitably sealed in any desired manner. In the construction illustrated, the base is mounted on a plate 40 having an annular upwardly extending projection 41 formed to enter into a corresponding recess in the base and to cooperate with a packing ring 42 arranged in the recess. Endwise movement of the shaft may be opposed at the upper end of the shaft by means of a suitable plunger or pin 44, the lower end of which extends into the bearing bushing 19 and which may be pressed downwardly against the upper end of the shaft by means of a coil spring 45, the ten-

sion of which may be adjusted by means of a threaded plug 46 arranged within the tubular part 20 of the head 18. If desired, a ball may be interposed between the upper end of the shaft and the stem or plunger 44. By adjusting the lower screw 36, the shaft may be adjusted to correctly position the rotor within the pump housing 9 and by adjusting the threaded screw plug 46, the pressure which the spring 45 exerts on the upper end of the shaft may be varied as desired. Any other means for mounting the shaft 16 in the pump chamber or housing may be provided.

In the operation of the apparatus thus far described, assuming that the inlet duct 7 is connected with a source of liquid to be pumped and the discharge passage 8 with a suitable delivery pipe for the liquid and assuming the motor is started in operation by connecting the terminals of the stator winding with a suitable supply of alternating current, it will be obvious that liquid will be pumped by the impeller from the passage 10 to the discharge passage 8. The hole 15 in the partition 14 is in communication with the liquid passage 18 through the housing 8 of the pump, and consequently, liquid can pass into the lower part of the tubular portion 5 of the housing and will rise in the housing until the pressure of the entrapped gas in the upper part 20 of the housing equals the pressure in the lower part of the housing, whereupon this gas will prevent further entrance of liquid into the upper part of the housing. The rotor 27 of the motor will, consequently, operate in a gaseous medium where its resistance to rotation is much less than when located in a liquid medium, thus greatly increasing the efficiency of the pumping apparatus. Furthermore, the rotor will be unaffected by any corrosive action of the liquid. The partition 14 serves to prevent splashing or surging of the liquid while being pumped in the lower part of the housing from being transmitted into the upper part thereof. By providing a pneumatic dome in the upper part of the housing, the need for stuffing boxes is entirely eliminated, and these stuffing boxes have heretofore been a source of continuous trouble with pumps of this type because of the fact that the packing and lubricant used in the stuffing boxes was readily attacked by liquids being pumped, thus producing leaks, which are dangerous and very objectionable when liquids such, for example, as liquid chlorine are being handled. When the pump is started in operation, the upper part of the housing will, of course, contain air and this air will be entrapped and compressed in the upper part of the housing, but some of the liquid which is being pumped may be vaporized and such vapor will, consequently, become mixed with the air in the upper part of the housing.

It is necessary to make sure that the temperature of the liquid does not rise to a point at which the liquid becomes excessively corrosive or easily vaporized, and for this purpose, I preferably provide the pumping apparatus with heat responsive means which may be connected in such a way as to interrupt the operation of the pump when parts thereof become excessively heated, or to actuate a warning signal.

This may be accomplished in any suitable or desired manner, for example, as illustrated diagrammatically on the drawing in which 50 and 51 represent thermo-responsive members located in any suitable or desired position on the pumping apparatus. For example, the member 50

is located so as to be responsive to changes in temperature of the pump housing 9, and the member 51 being responsive to temperatures of the stator of the induction motor. These devices are so constructed that current flowing through the same will be interrupted when the temperature in either thermostatic device becomes excessive. These two devices are preferably connected in series through a conductor 52 leading from a suitable supply of current, a conductor 53 connecting the two thermo-responsive members and conductors 54 and 55 leading to a relay 56 which normally holds a switch member 58 in circuit closing position against the action of a spring 59. This switch is in a conductor 60 leading to one of the terminals of the stator winding, the other terminal being connected by a conductor 61 to a suitable source of alternating current. Another conductor 62 leads from this source of current to a terminal with which the switch member 58 contacts when the motor is in operation. Consequently, if either of the two thermo-responsive members becomes excessively heated, the circuit including these members will be broken, thus causing the magnet 56 to release the switch member 58 to open the circuit to the motor. Any other connections for accomplishing this result may be used.

I claim as my invention:

1. A pumping device for use with corrosive and/or poisonous liquids, which includes an upright cylindrical chamber made of non-magnetic material having a head for the upper end thereof forming a gas-tight seal therewith, said cylinder and head forming a pneumatic dome, a centrifugal pump housing secured in air-tight relation to the wall of the lower portion of said cylindrical chamber and having inlet and discharge passages for the liquid and having a central opening forming a connection between said pump housing and said chamber, an impeller in said housing, a shaft on which said impeller is secured and which extends through said central opening of said pump housing without closing said opening, a bearing for said shaft arranged on said head of said cylindrical chamber and located within the air space in said

chamber and another bearing for the lower end of said shaft, said other bearing being located in a bore in said housing, said shaft terminating in said bore and the outer end of said bore being tightly sealed, an induction motor having a stator arranged on the exterior of the upper portion of said cylindrical chamber and having a rotor arranged within said upper portion of said chamber and secured to said shaft, said cylindrical chamber being of such height as to provide a clear space below said rotor which is at least equal in height to the space from the lower end of said rotor to said head, said cylindrical chamber forming a pneumatic dome in which said rotor operates above the level of the liquid in said cylinder.

2. A pumping device according to claim 1, in which the upper end portion of the wall of said cylindrical chamber extending about said rotor 20 and to the upper end of said wall is of materially smaller cross section than other portions of said cylindrical chamber and in which said stator includes a core which may be slid over said upper end portion of said cylindrical chamber and 25 which fits tightly about said portion of smaller cross section to reinforce the same against pressure within said cylindrical chamber.
